(57) **CLAIM**

(21) Appl. No.: **29/243,828**

The ornamental design for a surface configuration of a front spoiler for a vehicle, as shown and described.

(22) Filed: **Dec. 1, 2005**

DESCRIPTION

(30) **Foreign Application Priority Data**

Jun. 2, 2005 (EM) 000352521-0001

FIG. 1 is a left perspective view of a first embodiment of a surface configuration of a front spoiler for a vehicle according to my novel design; and

(51) **LOC (8) Cl.** **12-16**

FIG. 2 is a left side view thereof.

(52) **U.S. Cl.** **D12/181; D12/196**

FIG. 3 is a right perspective view of a second embodiment of the surface configuration of a front spoiler for a vehicle according to my novel design; and,

(58) **Field of Classification Search** D12/169, D12/196, 190, 90-92, 171, 181; 296/180.1-180.5; 293/102, 113, 115, 120; 280/727, 770, 848; 180/903

FIG. 4 is a right side view of FIG. 3.

See application file for complete search history.

The broken lines are for illustrative purposes only and form no part of the claimed design.
